OBSTETRICAL AND DELIVERY OPERATING
TABLE

Hyman Robert Shampaine, Clayton, Mo.

Application March 23, 1949, Serial No. 82,945

6 Claims. (Cl. 311—7)

1

This invention relates in general to medical operating tables and, more particularly, to certain new and useful improvements in obstetrical and delivery operating tables.

The primary object of the present invention is to provide an obstetrical table which may be elevated to various heights and tilted through a full range of angular positions from the Trendelenburg position to the reverse Trendelenburg position.

It is another object of the present invention to provide an obstetrical table which is uniquely constructed so that all movements may be readily and conveniently controlled by the anesthetist from the head end of the table.

It is also an object of the present invention to provide an obstetrical table having a main body-supporting portion and an underslung drawer-like leg-supporting portion arranged to move horizontally and vertically without any appreciable angular rocking or swinging movement so that the table can be used either as a labor bed or a delivery table, as necessity requires, and may be quickly transposed from one such function to the other smoothly and without danger of jarring or otherwise affecting the patient.

It is another object of this invention to provide an obstetrical table having a section for supporting a patient's legs, which section is normally concealed within the table and is freely shiftable therefrom into outward operative position.

A further object of the present invention is to provide a shiftable leg supporting section having a cushion-containing receptacle which is elevated by unique means into co-planar alignment with the top surface of the table after the section has reached a position forward of the table.

An additional object of the present invention is to provide locking means cooperable with the cushion receptacle whereby unauthorized depression of said receptacle is prevented when the legs supporting section is in operative position.

A further object of the present invention is to provide an obstetrical table which is durable, economical in construction, and reliable in operation.

With the above and other objects in view, my invention resides in the novel features of form, construction, arrangement, and combination of parts presently described and pointed out in the claims.

In the accompanying drawings (5 sheets):

Figure 1 is a side elevational view of an obstetrical table constructed in accordance with and embodying the present invention;

Figure 2 is a top plan view of the obstetrical table;

2

Figure 3 is a longitudinal sectional view taken along line 3—3 of Figure 2;

Figure 4 is an end elevational view of the obstetrical table;

5 Figure 5 is a transverse sectional view taken along line 5—5 of Figure 2;

Figures 6 and 7 are sectional views taken along lines 6—6 and 7—7, respectively, of Figure 1;

10 Figure 8 is a fragmentary sectional view taken along line 8—8 of Figure 6;

Figures 9 and 10 are fragmentary sectional views taken along lines 9—9 and 10—10, respectively, of Figure 7;

15 Figure 11 is a fragmentary sectional view taken along line 11—11 of Figure 9;

Figure 12 is a fragmentary sectional view taken along line 12—12 of Figure 10;

19 Figure 13 is a fragmentary sectional view taken along line 13—13 of Figure 3; and

20 Figure 14 is a fragmentary side elevational view of the obstetrical table with the leg section thereof in retracted position.

Referring now in more detail and by reference characters to the drawings which illustrate a preferred embodiment of the present invention, A

25 designates an obstetrical table having a generally rectangular base 1 provided with leg formations 2 at the four corners thereof. Concealed within each leg formation 2 is a suitably mounted caster

30 3 optionally maintained in upper, locked position or lower, rolling position by operatively connected pedal extensions 4, 5, projecting outwardly through slots 6, 7, respectively, in the rearward side of the base 1. Suitably mounted on the base

35 4 is a pedestal or column member 8 having housed therein a cylinder 9 vertically shiftable by conventional hydraulically operated means (not shown) arranged for actuation by a pedal 10 which extends outwardly through a slot 11 in the pedestal 8.

40 A plate-like casting 12 is secured to the upper end face of the cylinder 9 by screws 13, said casting 12 being integrally provided with a depending skirt 14 and spaced parallel upstanding bosses 15, 15'.

Extending through suitable aligned apertures in the bosses 15, 15', is a pivot shaft 16 secured at its ends in the central portions of spaced, parallel longitudinally extending sections 17, 17',

50 of a main frame 18 of a body-section 19, which comprises upstanding parallel side walls 20, 21, which, at their rearward ends (reference being had to the left of Figure 1) are turned inwardly in the provision of relatively narrow support walls 20', 21', with the rearward end of the body-section 19 being open therebetween, as at

22. Secured to the forward and rearward end of the upper margins of the walls 20, 21, are the ends of transversely attending angle sections 23 and similar angle sections 24 are secured along the upper margins of said walls 20, 21. Secured to the angle sections 24 are the ends of a plurality of parallel transverse slats 25 which support a pad or cushion 26 disposed over the chamber-like interior of the body-section 19, the latter being open at its forward end, as at 27.

The main frame 18 comprises upstanding cut-out side walls 28, 28', integrally connected by transverse parallel brace bars 29, 30. Upstanding from the forward margin of the bar 29 at either end thereof are relatively short flanges 31, 31', integrally joined at their inner ends to the rearward end of the sections 17, 17', respectively, which are integrally connected at their forward ends to the inner ends of short transverse walls 32, 32', which are equal in length, and parallel to, flanges 31, 31'. The sections 17, 17', are further integrally connected to the side walls 28, 28', by walls 33, 33', which are parallel to and positioned rearwardly of the walls 32, 32', respectively. The walls 32 and 33, and 32' and 33' are each provided on their upon margins with elevated portions, as at 34, and are joined by longitudinal partitions 35, 35', respectively, extending therebetween in parallel relation to the sections 17, 17', respectively.

Journalized in and projecting at its ends through the rear support wall 21' and the transverse flange 31' is a shaft 36, rigidly provided on its rearwardly projecting end with a hand wheel 37. On the forward end of the shaft 36 there is secured a bevel gear 38 meshingly engaged with a pinion 39 secured on one end of transverse shaft 40 journaled by bearings 40' and extending through the sections 17, 17', and suitable apertures in spaced upstanding legs 41, 41' of a bracket 42 disposed between the sections 17, 17', as may best be seen in Figure 5. Secured upon the shaft 40 inwardly of the legs 41, 41', is a bevel gear 43 engaged with a pinion 44 mounted on the upper projecting end of a vertically disposed screw shaft 45, of the so-called Trendelenburg type, extending through the bracket 42 and supported therein by a thrust bearing 46 and a washer 47. Near its lower end the screw shaft 45 is engaged by a screw nut 48 provided with diametrically opposed relatively shallow drill-holes 49, 49', for receiving the ends of pivot bolts or trunnion members 50, 50', respectively, mounted on opposite sides of the lower end of a support arm 51 secured at its upper forward end by screws to the casting 12.

By rotation of the shaft 36 through operation of the hand wheel 37 the table 19 may be pivoted about the axis of the pivot shaft 16 to facilitate administration of requisite treatment to any particular patient. It should be noted that the screw nut 48 is pivotable about the pivot bolts 49, 49', thereby permitting the screw shaft 45 to be swung about said pivot as the screw 45 is threaded downwardly or upwardly through the nut 48, as necessary, to raise or lower the body-section 19, thus assuring operative engagement at all times between the gear 43 and the pinion 44.

Journalized in and projecting through the rear support wall 20', the flange 31, and the walls 32, 33, is a shaft 52, parallel to and in the same plane as the shaft 36 and having mounted on its rearwardly projecting end a hand wheel 53. Secured on said shaft 52, intermediate the walls 32, 33, is a worm gear 54 meshingly engaged

with a concave gear 55 which is suitably mounted on one end of a transversely extending shaft 56, journaled by a bearing 57 in the partitions 35, 35', and extending through suitable apertures 58 in the sections 17, 17'. Mounted on the shaft 56 by collars 59, 59', adjacent the inwardly presented face of each partition 35, 35', are spur gears 60, 60', respectively. The gears 60, 60', are meshingly engaged with longitudinally extending gear racks 61, 61', adjustably secured by screws 62, 62', to flanges or ribs 63, 63', respectively, depending from the underside of a bottom plate 64, which, as will presently be described, is a part of the actuator frame f of the leg section 65. Threaded through suitable apertures in the plate 64 are adjustment screws 66, 66', their lower end abutting against the upper margin of the gear racks 61, 61', respectively, whereby vertical adjustment of the racks 61, 61', may be accomplished.

The leg section 65 is normally disposed in a concealed manner within the chamber-like interior of the body-section 19, but through driving cooperation of the spur gears 60, 60', 25 and the gear racks 61, 61', respectively, the leg section 65 may be optionally shifted from said concealed position to a position forwardly of the body-section 19 for supporting the legs of a patient, as will now be more fully described.

30 Secured to the opposite longitudinal margin of the bottom plate 64 are upstanding parallel side plates 67 which are outwardly flanged at their upper and lower margins in formation of a substantially rigid channel. Each of the side plates 67 is provided with a pair of spaced, camming slots s, each slot extends from a point adjacent the lower margins of the side plates 67 rearwardly and upwardly at an angle of approximately 60° thereto, terminating at its upper end in a second short locking-dwell 68, adjacent and parallel to the upper longitudinal margin of the side plates 67. Also provided in each of said plates 67, rearwardly of each slot s, is a longitudinal slot 69, all as best seen in Figure 9.

45 Movable disposed within each slot s is a ball bearing roller 70 of the cam-follower type, mounted on a roller shaft 71, extending through each slot s and having a second roller 72, mounted on its outer end. The inner end of each shaft 71 extends through a spacing washer 73 and threadedly mounted in a flange 74, depending from the side wall of a rectangular cushion-frame 75 designed to support a cushion or pad 76.

50 Each roller 72 is disposed between a pair of upstanding guides 77, 78, which are suitably secured to longitudinal plates 79, each being spaced outwardly from and parallel to one of the plates 67. Said plates 79, being inwardly turned at their forward margins in the provision of flanges 79', are longer than the plates 67, and are connected at their rearward ends by a support bridge 80 and at their forward ends by a spacer rod 80'.

55 Secured to the outer face of each of the plates 79, is a channel-shaped slide-rail 81 for cooperation with rollers 82 spacedly mounted on the inner faces of each of the side walls 20, 21, of the frame 18. Also secured to the outer faces of each of the plates 79, and extending above the upper margins thereof, are channel shields 83 which are curved inwardly at their upper margin in vertically spaced covering relation to the upper margins of the plates 67 and the guides 77, 78. (Figure 7.) Extending through each of 70 the slots 69 in the plates 67 are roller shafts 84

threadedly mounted in blocks 85, welded or otherwise, suitably mounted upon the inner faces of the plates 79. Threadedly mounted in and extending through the plate 79 in axial alignment with each roller shaft 84 is a set screw 86 adapted to permit locking adjustment of the roller shafts 84. Mounted on each roller shaft 84 and disposed within one of the slots 69 is a roller 87.

Extending through the plate 79 in the rearward lower portion thereof is the outer end of a short shaft 90 which extends through a bearing collar 91 welded on one of the inner faces of the plate 79. Pinned to the shaft 90 is a collar 92 to one end face of which is welded a rocking arm 93, having a forwardly and upwardly presented, inclined cam face 93'. Inwardly of the rocking arm 93, the shaft 90 projects through an aperture 94 in the forward end of a bracket or stabilizing arm 95, which is formed with an offset bend and is secured by bolts 96 to the inner face of the plate 79. (Figure 12.) Encircling the inwardly projecting end of the shaft 90 is a spring 97 anchored at its one end by extending through suitable apertures in the shaft 90 and anchored at its other end in the bracket 95, whereby upon rotation of the shaft 90 tension may be effected on said spring 97. Pinned upon the outer end of the shaft 90 is a collar 98 and welded to the outer end face thereof is an extending stop latch 99, having a semicircular recess 100 extending upwardly from its lower margin for optional locking engagement with a stop pin 101 projecting inwardly from the forward portion of the side wall 28 of the frame 18. It is to be particularly noted that the rear portion of the stop latch is vertically extended whereby the rearward side of the recess 100 is continuous with an elongated portion or end extension 102. (Figure 10.) Extending outwardly from the adjacent plate 67 is a pin member 103 disposed for optional contact with the cam face 93' of the rocking arm 93 as will be more fully described hereinafter.

Disposed closure-wise between the ends of the plates 79, is a cover plate 104 secured to the flanges 79' of the plates 79 by elongated screws 105, each having a spring 106 encirclingly disposed about its shank, said spring 106 abutting at its ends against the inner face of the flange 79' and washer 107 mounted about each screw 105 adjacent a nut 108 threaded thereon.

Mounted on the outer faces of each side wall 20, 21, adjacent their forward ends is a swivel socket 109 for adjustably supporting a knee crutch member 110.

During certain stages of child-bearing the body-section 19 of the obstetrical table 12, is employed with the leg section 65 in retracted position. As noted above, the body-section 19 may be elevated or depressed, as necessary, about the axis of the pivot shaft 16 to facilitate treatment. However, at other stages of child-bearing, the leg section 65 may be moved out of the interior of the body-section 19 into aligned position forwardly thereof with the upper surface of the pad 76 in co-planar alignment with the upper surface of the pad 26, whereby the patient's legs may be comfortably supported in outstretched position. This movement of the leg section 65 is accomplished in the following manner: The shaft 52 is rotated by manual operation of the wheel 53 whereby through the gears 54, 55, rotation is imparted to the transverse shaft 56. The spur gears 60, 60', drivingly engage the gear racks 61, 61', respectively.

It will be noted that the leg section 65, in effect, moves in and out of the opening 21 from concealed position within the body-section 19, as shown in Figure 14, to extended position, as shown in Figure 1. The cushion frame 75 is disposed within and forms a part of the leg section 65, being confined therein by engagement of its four rollers 72 within the four pairs of vertical guides 77, 78. It will thus be seen that the cushion frame 75 and its associated parts cannot move longitudinally with respect to the plates 79 and is therefore limited to up and down movement within the pairs of guides 77, 78. On the other hand, the actuator frame f, also carried by and forming a part of the leg section 65, is free to shift length-wise with respect to the leg section 65 through the short limits of movement permitted by inter-engagement between the rollers 87 and the slots 69 of the side plates 67. This inter-engagement between the rollers 87 and the slots 69, however, prevents the plates 67 from moving up and down. Thus, it will be seen that the leg section 65 carries a cushion frame 75 which is free to move only along a length perpendicular to the general plane of movement of the leg section 65 and, at the same time, the leg section 65 also carries an actuator frame f which is free to move only to a limited extent in a line which is parallel to the general plane of movement of the leg section 65.

As the hand wheel 53 is rotated and the spur gears 60, 60', drive the racks 61, 61', outwardly the leg section 65 is, of course, in concealed or withdrawn position and the cushion frame 75 is in lowered position, that is to say, in a position wholly confined within the limits of the leg section 65. In this position the rollers 72 are engaged in the lower forward ends of the slots s and since the weight of the cushion frame 75, together with the cushion 76 and other related structures, is substantially greater than the functional resistance of the leg section 65 to outward movement, the actuator frame f, the cushion frame 75, and leg section 65 will be thus held together against relative longitudinal translation and the entire leg section 65 with all its contained parts will be moved outwardly into extended position by the movement of the racks 61, 61'. It may be noted in this connection that by appropriate adjustment of the screws 62, 62', 64, the racks 61, 61', may be positioned to permit the proper amount of contact with the gears 60, 60', to insure maximum smoothness of operation.

As the leg section 65 reaches fully extended position, as shown in Figure 1, the depending end extension 102 of the stop latch 99 will engage the stop pin 101. The actuator frame f, however, is free to continue its forward movement by longitudinal translation relatively within the now stationary leg section 65 within the limits of the length of the slot 69. Furthermore, the cushion frame 75 and the cushion 76 supported therein are now positioned outwardly in the clear beyond the transverse end of the body section 19 and are free to move upwardly into elevated position. Thus, continued turning movement of the hand wheel 53 will cause the rack 61, 61', and the actuator frame f to continue their outward longitudinal movement since the rollers 72 of the carriage frame are engaged in the angular slots s and are at the same time preventing, by reason of inter-engagement between the rollers 72 and the guides 77, 78, from further longitudinal movement with the actuator frame f, the rollers 72

are forced to ride upwardly, by reason of interaction with the camming slots *s*, and finally, to ride into the locking dwells *68* whereby the cushion frame *75* and its supported cushion *76* are brought to rest in fully elevated position.

As the cushion frame *75* moves upwardly the pin *103* moves upwardly away from engagement with the inclined cam face *93'* of the rocking arm *93* and the stop latch *99* is forced downwardly under influence of the spring *97* bringing the recess *100* into engagement with the stop pin *101*, thereby locking the leg section *65* against length-wise movement in either direction. Consequently, when the hand wheel *53* is turned in the opposite direction the first movement which takes place in the leg section *65* is a retrogressive longitudinal translation of the actuator frame *f* and the cushion frame *75*, together with its supported cushion, is lowered into its original position wholly within the confines of the leg section *65*. As the cushion frame *75* returns to its fully lowered position the pin *103* again contacts the inclined cam face *93'* of the rocking arm *93* and swings the stop latch *99* upwardly disengaging the detent *100* from the pin *101*. At the same time the rollers *70* will have reached the lowermost position in the slots *s* and the actuator frame *f* will have reached its rearwardmost position of longitudinal translation relative to the leg section *65* so that the leg section *65* and actuator frame *f* again begin to operate as a single unit and the entire leg section *65*, together with all of its supported structure, will be withdrawn through the opening *27* into fully retracted position within the body section *19*.

It will be noted that the cover plate *104* which extends across the outer end of the leg section *65* is resiliently held in place by the springs *106*. Thus, if the fingers of either an attending nurse, physician or the appendages of the patient herself should accidentally happen to become caught between the rising cushion frame *75* and the cover plate *104* the latter would yield and any serious damage or injury would thus be avoided.

It should be understood that changes and modifications in the form, construction, arrangement, and combination of the several parts of the obstetrical table may be made and substituted for those herein shown and described without departing from the nature and principle of my invention.

Having thus described my invention, what I claim and desire to secure by Letters Patent is:

1. An obstetrical table comprising a pedestal, a hollow bed section mounted on the pedestal and having an opening across one transverse end, an open topped drawer-like frame mounted in and carried by the bed section for lengthwise shifting movement through the opening, a leg section disposed within the frame and confined therein for upward shifting movement solely in a direction at right angles to the direction of movement of the frame, slide means carried by the frame and being longitudinally shiftable in relation thereto, locking means actuated by the leg section when the latter is in downwardly shifted position within the frame, said locking means when so actuated being engaged with the slide means for holding the latter non-shiftably within the frame, means attached to the slide means for propelling the slide means, frame and leg section as a unit through the opening into and out of the bed section, stop means carried by the frame and being engageable with the bed section when the frame is in outwardly shifted position,

said leg section means being free for upward shifting movement when the frame is in such outwardly shifted position, whereby to permit longitudinal shifting movement of the slide

5 means after the frame has reached outwardly shifted position, and auxiliary means on the slide means engaged with the leg section for elevating the leg section responsive to longitudinal shifting movement of the slide means so that 10 the upper surface of the leg section is substantially co-planar with the upper surface of the bed section.

2. An obstetrical table comprising a bed section, a slide shiftably mounted beneath the bed section for movement in a substantially horizontal direction from retracted position in which 15 it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of substantially horizontal movement with the slide and 20 also up-and-down movement relative to the slide, and actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that 25 30 as the actuator means moves to and fro translationally relative to the slide the cushion frame will be shifted correspondingly up-and-down.

3. An obstetrical table comprising a bed section, a slide shiftably mounted beneath the bed section for movement in a substantially horizontal direction from retracted position in which it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of substantially horizontal movement with the slide and 40 also up-and-down movement relative to the slide, and actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that as the actuator means moves to and fro translationally relative to the slide the cushion frame will be shifted correspondingly up-and-down.

4. An obstetrical table comprising a bed section, a slide shiftably mounted beneath the bed section for movement in a substantially horizontal direction from retracted position in which it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of substantially horizontal movement with the slide and 45 also up-and-down movement relative to the slide, and actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that as the actuator means moves to and fro translationally relative to the slide the cushion frame will be shifted correspondingly up-and-down, and a lock engageable with the bed section for limiting the outward movement of the slide.

5. An obstetrical table comprising a bed section, a slide shiftably mounted beneath the bed section for movement in a substantially horizontal direction from retracted position in which it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of

substantially horizontal movement with the slide and also up-and-down movement relative to the slide, actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that as the actuator means moves to and fro translationally relative to the slide the cushion frame will be shifted correspondingly up-and-down, and a lock engageable with the bed section when the slide is in fully extended position and the cushion frame is in upwardly shifted position whereto to prevent movement of the slide in either direction while the cushion frame is in such upwardly shifted position.

5. An obstetrical table comprising a bed section, a slide shiftably mounted beneath the bed section for movement in a substantially horizontal direction from retracted position in which it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of substantially horizontal movement with the slide and also up-and-down movement relative to the slide, actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that as the actuator means moves to and fro translationally relative to the slide the cushion frame will be shifted correspondingly up-and-down, and driving means for propelling the actuator means to-and-fro.

6. An obstetrical table comprising a bed section, a slide shiftably mounted beneath the bed section for movement in a substantially horizontal direction from retracted position in which it is disposed beneath the bed section to extended position in which it projects outwardly from one transverse end of the bed section, said slide having spaced parallel side members, substantially vertical guides carried by the side members, a cushion frame carried by the slide and engaged within the guides so as to be capable of substantially horizontal movement with the slide and also up-and-down movement relative to the slide, actuator means carried by the slide and shiftably connected thereto for limited translational movement relative to the slide in the same direction as the slide moves in traveling from retracted to extended position, said actuator means being provided with cam-forming means inclined with respect to the direction of movement of the actuator means and being operatively engaged with the cushion frame so that as the actuator means moves to and fro translationally relative to the slide the cushion frame will be shifted correspondingly up-and-down, and an end plate disposed transversely and closurewise across the outer end of the slide, said plate being resiliently held in place so as to yield outwardly as the cushion frame is raised in the event that an unauthorized object is accidentally interposed therebetween.

HYMAN ROBERT SHAMPAINE.
